UNITED STATES PATENT OFFICE.

EMIL TYDEN, OF EVANSTON, ILLINOIS.

DRY-PIPE VALVE-ACCELERATING DEVICE.

Application filed August 25, 1923. Serial No. 659,332.

To all whom it may concern:

Be it known that I, EMIL TYDEN, a citizen of the United States, and resident of Evanston, in the county of Cook and State of Illinois, have invented certain new and useful Improvements in Dry-Pipe Valve-Accelerating Devices, of which the following is a specification, reference being had to the accompanying drawings, forming a part thereof.

The purpose of this invention is to provide an improved construction in a dry pipe sprinkler system for accelerating the opening of the dry pipe main valve upon the opening of a sprinkler head, with a specific purpose of preventing the opening of the main valve upon the occurrence of a minor negligible leakage in the air system, amounting to less than would occur through a single open sprinkler head. It consists in the elements and features of construction shown and described, as indicated in the claims.

In the drawings:

Figure 1 is a front elevation of a dry pipe valve casing with certain parts broken away to show the interseat chamber in section and equipped with devices embodying this invention.

Figure 2 is a side elevation of the same also partly broken away to show the interseat chamber in section.

Figure 3 is an enlarged sectional view of the construction contained in the casing, E, being taken substantially as indicated at section line 3—3 on Figure 1.

Figure 4 is an elevation of the casing, E, looking in the direction of arrow, 4, on Figure 3 and with certain parts broken away to reveal the interior structure.

Figure 5 is a horizontal section taken as indicated at line 5—5 on Figure 3.

Figure 6 is a view similar to Figure 2, showing modification.

Figure 7 is a view similar to Figure 3, showing modification.

Figure 8 is a detail elevation of operating connections shown in Figure 6.

Figure 9 is a section at line 9—9 on Figure 8.

Figure 10 is a detail section at the line 10—10 on Figure 8.

In the structure shown in the drawing, A is the dry pipe valve casing, B the water in-lead pipe, C the pipe leading to the sprinkler system which, in the normal condition of the apparatus, when set for its purpose, is oc-

cupied by air under pressure. D is the dry pipe main valve having the usual construction for seating at two concentric seats, A¹⁰ and A¹¹, between which there is the usual interseat chamber, a, in which the pressure is normally atmospheric, so that the super-atmospheric pressure, operating above the valve D, over the larger area defined by the outer seat A¹¹, as compared with the area defined by the inner seat A¹⁰, over which the water pressure is operative, insures the valve D being held seated by a super-atmospheric pressure in the system of about 30 lbs. against water pressure in the main which may reach 100 lbs. When a sprinkler head is opened, causing reduction of the super-atmospheric pressure in the system, which eventually results in the dry pipe main valve D being opened by the water pressure and the water thereby being sent to the open sprinkler head, it is desirable that the opening of the valve should be delayed as little as possible after the sprinkler head is opened and the reduction of air pressure in the system begins; but when only a single sprinkler head is opened by the fire, it may require a very appreciable length of time for the air pressure to be reduced so as to permit the dry pipe main valve to open. The purpose of the present invention is to cause the amount of reduction of air pressure in the system which will be experienced almost instantly upon the opening of a single sprinkler head, to result in overcoming the differential pressure upon the upper side of the valve which holds it seated, so that the valve will open almost instantly upon the opening of the sprinkler head. This is effected by means of devices which are sensitive to the slight reduction of pressure which occurs almost instantly upon the opening of the sprinkler head, and which, responding to that slight reduction, operate to open a communication from one of the pressure regions,—either the region of water pressure operating over the lesser area of the valve, D, or the region of air pressure operating over the greater area of the valve,—to the interseat chamber, a, below the dry pipe main valve, hereinafter referred to as the "atmospheric pressure chamber." These devices are designed with the view to responding, as indicated, to the reduction of pressure which follows the opening of a single sprinkler head, while not responding to less reduction of pressure which may result from

minor negligible leakages in the system. These devices will now be described.

Mounted upon the air pipe, C, leading from the dry pipe main valve casing to the sprinkler system is a casing, E, whose chamber is divided by partition, E³, into two compartments, E¹ and E², the partition, E³, has an aperture, e³, extending through it, and upon the side of said aperture, toward the compartment, E¹, there is constituted an expansible and reducible chamber by means of a flexible diaphragm, H, bound to the partition at its margin by the marginal flange, f, of a spider, F, which is sprung spherically away from the plane of the diaphragm and partition, E³, to afford space for the diaphragm to be expanded by pressure reaching it through the aperture, e³, in the partition, E³. At the center of the spider it has a hub, F¹, in which there is guided a plunger stem, K, having the foot, k, resting upon the center of the diaphragm; and a spring, L, housed in the hub, F¹, stopped at one end by a closure in the end of the cavity of the hub and at the other end by pin, l, inserted through the plunger stem, K, re-acts upon the plunger for pressing its foot, k, upon the center of the diaphragm. A pipe, W, leading from the air pressure region of the system and most conveniently from the pipe, C, immediately below the position at which the casing, E, is mounted on said pipe, communicates by way of a fitting, G, into and with both compartments of the casing, E. For such communication the fitting, G, consists of a pipe nipple exteriorly threaded throughout its length, having apertures, g, leading from its bore to an exterior annular groove or channel, g¹. The casing, E, has at its lower side a boss, e, through which there is extended a duct, e¹, which opens at one end by a port e² into the compartment, E¹. The casing wall is bored and threaded through the boss, e, for receiving the fitting, G. The bore for that purpose intersects the duct, e¹, and the groove or exterior annular channel, g¹, of the fitting is positioned in the lengths of the fitting, so that when the latter is screwed through the bore to a suitable distance for receiving the valve cage, hereinafter mentioned, the annular groove, g¹, registers with the duct, e¹, and thereby there is afforded communication from the axial bore of the fitting to the compartment, E¹. Said axial bore, itself leads into the compartment, E²; and, the inner end of the fitting is formed as a valve seat for a valve, G¹, which is retained and held normally seated by a cage-like cap member, G², which is screwed on to the inner end of the fitting, G, the stem of the valve being guided in an aperture at the center of the cap cage and being held normally seated by a spring, G³, coiled

around the stem of the valve and re-acting against the head of the valve and head of the cap. The spring, G³, is designed to be light as to its action on the valve, so as merely to insure being normally seated, but so as to yield readily to permit the valve to open freely for admission of pressure to the compartment, E². The operation of this construction as thus far described is that the pressure from the air pressure region of the system obtains access through the fitting, G, with substantially equal ease to both compartments, E¹ and E², and equally freely through the aperture, e³, in the partition, E³, to the right hand side of the diaphragm resting against the partition, E³, and to the left hand side of the diaphragm through the apertures f¹ of the spider, F, with the result that, normally, the diaphragm lies flat upon the partition, E³, being undisturbed by the pressure upon either side. But in case of reduction of pressure in the system to the extent which would be caused by the opening of a single sprinkler head, that reduction would be experienced in the chamber, E¹, as freely and quickly as the pressure is transmitted originally to that chamber because the relief will be back through the same passage, e¹, through which the pressure originally was admitted; but in chamber, E², the relief will be experienced only by the restricted escape of air through a small axial duct, g¹⁰, which is formed through the valve, G¹. And the result will be that upon such reduction of air pressure in the system, the diaphragm, H, will be stretched or expanded away from the partition, E³, into the spider, causing the plunger, K, to be thrust out through its bearings in the spider hub. The compartment, E¹, is connected by pipe, M, with the interseat or atmospheric pressure chamber, a, of the dry pipe main valve casing. This connection is made through a fitting, N, screwed into the casing, E, intruding into the compartment, E¹, thereof, said fitting having a seat for a valve, O, which seats in the direction of the pressure from the chamber, E¹, and is provided with a spring, R, re-acting for opening it against that pressure. The valve, O, has its stem, O¹, extending in both directions and guided at its opposite ends in guide spiders, O² and O³, screwed into the opposite ends of the fitting. The stem, O¹, protrudes beyond the guide spider, O², in the compartment, E¹, in position to be encountered by a lever arm, P¹, of the lever, P, fulcrumed in the casing one pivot indicated at p and having an oppositely extending weighted lever arm, P², and an upwardly extending catch arm, P³, adapted to be engaged by the catch nose, s, of the latch, S, pivoted in the casing and having a trip finger or lug, S¹, projecting across the end of the plunger stem, K, in

position to be encountered by the end of that plunger stem upon the least movement of the latter caused by the deflection of the diaphragm away from the partition, E^3 ; 5 and at this position of the latch, S , its catch nose, s , is in position for engaging the catch finger, P^3 , of the lever, P ; and said lever, P , is in position to have its catch finger, P^3 , engaged by said latch nose, when 10 the weighted arm of said lever is elevated and the opposite arm, P^1 , is depressed for holding the valve, O , positively seated against the re-action of the spring, R , tending to open it.

15 The entire operation of the device will now be understood to be that upon reduction of pressure in the air pressure region of the dry pipe system, the diaphragm, H , expanding into the spider and thrusting the 20 plunger, K , against the trip lug, S^1 , of the latch, S , disengages the latch nose, s , from the catch finger, P^3 , of the lever, P , whereupon the weighted arm of the lever descends and the valve-locking arm, P^1 , rises permitting 25 the valve, O , to be opened by the re-action of the spring, R ; and thereby the air pressure from the system, admitted through the fitting, G , freely to the chamber, E^1 , is transmitted freely past the valve, O , through 30 the pipe, M , to the interseat or atmospheric pressure chamber, a , of the dry pipe main valve. The air pressure from the system being thus introduced over the differential area of the dry pipe main valve, 35 destroying the difference between the pressures at the two sides of the valve by virtue of which the valve is held seated, the water pressure operating at the under side of the valve, being in excess of the now equalized air pressure at the two sides of the valve, opens the valve and floods the system. Such opening is practically instantaneous and is not delayed, as would be the case in the absence of the devices described, during the slow reduction of pressure in the system which would occur through one or a small number of open 40 sprinkler heads.

For resetting the device, when making the usual re-set of the entire dry pipe apparatus, it is necessary to obtain access to the mechanism in the casing, E , for seating the valve, O , and latching it seated. For this purpose there is provided in the upper side of the casing, E , an aperture closed by a screwed-in plug, Z , and this plug is connected by a chain, z , to the weight at the end of the lever arm P^2 . The chain has a swivel connection with the plug, so that the rotation of the plug will not tangle the chains. The chain is long enough to permit the weight to fall freely to the full extent necessary to permit the valve, O , to open wide. For setting the device the operator unscrews the plug and pulls up the weight until the catch finger, 50 P^2 , is engaged by the latch nose, s . To cause such automatic engagement, the latch is provided with a spring, s^3 , coiled around its pivot stud and engaged at one end with the latch and at the other end with the 55 casing.

In Figures 6, 7, 8 and 9 there is shown a modification of the structure, adapting it for admitting pressure to the atmospheric pressure chamber, a , directly from the air pipe C , that is avoiding passing the air through the casing, E , and that casing having no communication except the inlet from the pipe, C . In this modification, in the drawings of which,—Figures 6, 7, 8 and 9,—the parts identical with the corresponding parts of the previous figures are similarly lettered, the pipe nipple G^* , which is substituted for the nipple, G , of the previously described figures, is blind at the outer end 75 and has an exterior hexagonal flange g^* , for screwing it in and stopping it. A fitting, N^* , substituted for the fitting, N , of the preceding figures, has the valve, O , seating inwardly at the seat, n , with the spring, R , tending to 80 initially seat it. The pipe, W , admitting air pressure from the pipe, C , is connected to said fitting, N^* , instead of to the nipple, G , of the previous figures, and said fitting, N^* , 85 communicates at a point beyond the valve seat, as seen at n^1 , with a duct, e^1 , leading to the nipple, G^* , for communication of pressure between the chambers, E^1 and E^2 , past and through the valve, G^1 , as in the preceding figures. The shaft p^2 of the lever, P , 90 in this construction, protrudes through the casing wall and has an exterior lever arm, P^4 , which, at the normal locked position of the lever, P , shown in Figure 8, engages the arm, Q , of the bell-crank lever, Q^1 , fulcrumed about the stem of a turn-cock valve, V , which controls access through the pipe, M^* , from the air pressure region of the system to the atmospheric pressure chamber, a , of the dry pipe valve casing, said pipe, 95 M^* , being conveniently made as shown, a branch of the pipe, W . At the position at which the bell-crank lever is held by the engagement therewith of the lever arm, P^4 , 100 the weighted arm Q^1 of the bell-crank lever 105 Q is at one side of the vertical plane of its fulcrum, and as soon as the arm, q^1 , is released by the movement of the lever, P^4 , which results from the falling of the weighted lever, P , upon release of the latch, S , the weighted arm, Q^1 , falls, and the bell-crank lever Q is rocked about its fulcrum, engaging 110 by the arm, Q^1 , a co-operating pin, b , on the stem of the turn-cock valve member, and opens the valve admitting pressure from 115 the air pressure region (pipe C), to the atmospheric pressure chamber, a , at the same instant that the valve, O , shuts off the communication of the air pressure region (pipe C), with the casing, E . Air being trapped 120 125 130

24
in the pipe, W, from the pipe, C, to the casing, E, prevents the water which ultimately replaces the air in the system from following the air through the pipe, W, to the casing, as is liable to happen in the first described construction. The operation for resetting the device in this form is the same as in the form of the previously described figures.

10 I claim:

1. In a dry pipe sprinkler system in combination with a dry pipe main valve, constructed for exposing different areas to the water and air pressure respectively at its opposite sides, and having for that purpose at the water inlet side, a chamber in which the pressure is normally substantially atmospheric; a passage leading from the region of one of said pressures to said chamber; a valve controlling said passage; an expandible and collapsible device exposed to the air pressure from the system reaching different areas of the movable wall of said device through unequal ports, whereby change of air pressure in the system causes temporarily unequal pressure at different areas; a chamber in which said device is enclosed; a lever in said chamber; means actuated by said lever for controlling the opening of said valve; a latch in the chamber engaging the lever to lock it in position for holding said valve closed, and connections from the latch to said device for disengaging the latch for releasing the lever upon movement of said device.

2. In the construction defined in claim 1, foregoing, exteriorly accessible means for resetting the lever in latched position.

3. In the construction defined in claim 1, foregoing, the expandible and collapsible device, comprising a single diaphragm, the casing comprising two compartments separated by a partition against one of which the diaphragm is mounted in one of the compartments, said partition having an aperture for air access through it from the other compartment to the side of the diaphragm proximate to said partition, the two compartments having respectively vent communications leading back toward the air pressure system through unequal ports, the compartment in which the diaphragm is situated having the greater port.

4. In the construction defined in claim 1, foregoing, the expandible and collapsible device comprising a single diaphragm and a casing within which it is mounted, comprising two compartments separated by a parti-

tion against one side of which in one of said compartments the diaphragm is mounted, 60 said partition having an aperture affording free air access through it from the other compartment to the diaphragm; a fitting affording air connection from the system to the chamber and having separate communications with the two compartments, both relatively unrestricted, a check valve controlling said communication of the fitting with the compartment opposite the diaphragm, said valve opening for air access to said compartment and having an air passage through it which is restricted relatively to the communication of the fitting with the other compartment.

5. In the construction defined in claim 1, 75 foregoing, the passage for admitting pressure to the atmospheric pressure chamber being independent of the chamber containing the expandible and collapsible device.

6. In the construction defined in claim 1, 80 foregoing, a valve which controls communication of the air pressure region with the chamber containing the expandible and collapsible device, said valve being positioned 85 for seating by pressure from the system to cut off the same from said chamber; means in said chamber for locking said valve open, and connections from the expandible and collapsible device for releasing the locking means to permit the valve to be closed by 90 the air pressure upon the movement of the wall of said collapsible device which results upon the occurrence of the unequal pressure 95 on its different areas respectively; whereby air is held in the passage of communication from the system to said chamber and prevent access of water from the system to said chamber.

7. In the construction defined in claim 1, 100 foregoing, the chamber which encloses the expandible and collapsible device having a screw-plug-closed aperture; a screw plug therein; the valve-controlling lever being weighted for normally operating by gravity 105 to operate the valve which controls the admission of pressure to said chamber, said screw plug having a flexible connection with said lever for operating it by means of the plug when the latter is unscrewed from said aperture for seating the lever at latched 110 position to permit the valve to be seated.

In testimony whereof, I have hereunto set my hand at Chicago, Illinois, this 16th day of August, 1923.

EMIL TYDEN.
